UNITED STATES PATENT OFFICE.

JOHN DAVIDSON, OF TUTBURY, ENGLAND.

INTERNAL-COMBUSTION ENGINE.

Application filed April 11, 1924. Serial No. 705,916.

To all whom it may concern:

Be it known that I, JOHN DAVIDSON, a British subject, residing at The Elms, Tutbury, Stafford, England, have invented certain new and useful Improvements in Internal-Combustion Engines, of which the following is a specification.

This invention relates to improvements in and connected with internal combustion engines of the single acting two cycle type.

The primary object of this invention is to produce a single crank internal combustion engine which will be well balanced, silent in working, and efficient.

According to my invention an internal combustion engine comprises two working cylinders connected at their inner ends by a common combustion chamber, working pistons in the working cylinders coupled to the crank shaft to reciprocate simultaneously in the same direction, a pump operatively connected to the crank shaft to reciprocate simultaneously in opposite direction to that of the working pistons, ports in one of the working cylinders connected to the pump and ports in the other working cylinder for the escape of exhaust gases.

Additional pairs of working cylinders may be provided to act with the pump which is then connected to a crank pin to balance both or all of the pairs of working pistons.

Furthermore, according to my invention, I provide an internal combustion engine with two or more pairs of working cylinders wherein the cylinders of each pair are connected together by a common combustion chamber, with more than one pump for supplying combustible mixture or scavenging air to the working cylinders, the operative connections between the working pistons and pump pistons on the one hand and the engine shaft on the other hand being arranged to cause the pistons to balance one another.

The pairs of working cylinders may be arranged in various different positions and a valve may be employed to control the pump or pumps.

In order that my invention may be fully understood and more readily carried into practice, I have caused to be appended hereto six sheets of drawings illustrating various examples thereof, wherein—

Fig. 1 is a view in elevation, partly in section, of the improved engine.

Fig. 2 is a transverse section through the same.

Fig. 3 is a developed section on line A—A of Fig. 2 illustrating a modified arrangement.

Fig. 4 is a plan, and Fig. 5 a vertical section developed on the line B—B of Fig. 4, of a further modified form.

Fig. 6 is a transverse section, and Fig. 7 a vertical section developed on line C—C of Fig. 6, showing a further modified form.

Figs. 8 and 9 are horizontal and vertical sections respectively in diagrammatic form of a further modification.

Figs. 10 and 11 are transverse and vertical sections in diagrammatic form of a further modification.

Referring to the drawings two working cylinders 1 and 2 are arranged. The cylinders 1 and 2 are of equal diameter and are connected at their inward end by a common combustion chamber 3. Pistons 4 and 5 are arranged to work in the cylinders 1 and 2 and are coupled by connecting rods 6 and 7 directly to one crank pin 8 of a crank shaft 18. Consequently the two pistons 4 and 5 reciprocate together or simultaneously in the same direction.

Formed in the barrel of the cylinder 2 is a port 9 for the admission of the fuel, and in the cylinder 1 a port 10 is formed to allow the exhaust gases to escape; both these ports being so placed that they are uncovered by the pistons 4 and 5 when nearing the outward end of the stroke.

A pump cylinder 11 containing a pump piston 12 is placed along side the working cylinders 1 and 2 for distribution of the fuel which may be petrol, paraffin or gas. The pump piston 12 is connected by a connecting rod 13 to a crank pin 14 of the crank shaft 18, the crank pin 14 being angularly displaced about 180 degrees to the crank pin 8. The barrel of the pump cylinder 11 has an entrance port 15 controlled by the pump piston 12, and an outlet port 16 connected by a passage 17 to the inlet port 9.

With a view to avoiding having to adopt hinged connecting rods, or forming the crank pin end of one of the connection rods so as to clip the other in order to keep the cylinders in one line at right angles to the crank shaft, I stagger the working cylinders to a small extent. Figures 1 to 3 illustrate a construction having staggered working cylinders wherein the two working cylinders 1 and 2 are placed one on each side of a line drawn at right angles to the crank shaft.

through the centre of the crank pin 8, so that uncovers the port 15 leading to the fuel supply and draws in the charge. On the upward stroke this charge is slightly compressed and as will readily be seen, when the pump piston 12 is nearing the top of its stroke the working piston 5 commences to open the inlet port 9, thus allowing the charge of fuel to be delivered into the working cylinders 1 and 2. It will be observed that while the working pistons 4 and 5 are performing their outward stroke, the pump piston 12 is performing its inward stroke, the charge being thus compressed in the pump cylinder 11 preparatory to rushing into the working cylinders 1 and 2 when the inlet port 9 is uncovered by the working piston 5.

The cylinder of the fuel distributing pump 11 is placed along side the working cylinders 1 and 2 and the piston 12 thereof is connected by the connecting rod 13 to the crank pin 14 which is situated directly opposite the crank pin of the working pistons 3 and 4.

In the case of any of the engines above described the fuel pump is of the single acting type, consisting of a plain piston 12 directly connected to its crank pin 14 in the well-known manner, and I make the pump piston 12 of equal weight to the two working pistons 4 and 5, and I also make the connecting rod 13 of the pump piston 12 of equal weight to the two connecting rods 6 and 7 the working pistons 4 and 5, in order that good balance may be obtained.

Figure 3 which shows the working pistons 4 and 5 and the pump piston 12 in different positions from those shown in Figures 1 and 2 illustrate how the pump piston by performing its inward stroke while the working pistons are performing their outward stroke acts to balance the working pistons which in turn act to balance the pump piston. The arrows indicate the passage of the gas or vapour before and after combustion.

The fuel pump may be of the single acting valveless type, the inner end of the cylinder 11 being directly connected by the suitable port 16 to the inlet port 9 of the working cylinder 2. A port 15 is formed in the barrel of the pump cylinder 11 adapted to be uncovered near the end of the outward stroke of the pump piston 12, and the carburettor or fuel supply is directly connected to this port 15.

The engine above described operates as follows:—Assuming that the two working pistons 4 and 5 are at the inner end of the stroke or in the case of a vertical engine are at the top of their stroke and the charge is compressed in the common combustion chamber 3, the charge is fired and the two pistons 4 and 5 move outwards together. The piston 4 when nearing the end of the stroke uncovers the exhaust port 10 and allows the gases to escape and immediately afterwards the piston 5 uncovers the inlet port 9 allowing the charge to be admitted and drive out the remainder of the exhaust gas. On the return stroke of the pistons 4 and 5 the charge is compressed and fired and the same operation repeated.

During the upward stroke of the working pistons 4 and 5 the pump piston 12 moves downwards thus creating a slight vacuum in the pump cylinder 11, but when nearing the outward end of its stroke it

supplies the port 15 leading to the fuel supply and draws in the charge. On the upward stroke this charge is slightly compressed and as will readily be seen, when the pump piston 12 is nearing the top of its stroke the working piston 5 commences to open the inlet port 9, thus allowing the charge of fuel to be delivered into the working cylinders 1 and 2. It will be observed that while the working pistons 4 and 5 are performing their outward stroke, the pump piston 12 is performing its inward stroke, the charge being thus compressed in the pump cylinder 11 preparatory to rushing into the working cylinders 1 and 2 when the inlet port 9 is uncovered by the working piston 5.

Only one arrangement of the engine has been described but it will readily be seen that this improvement may be applied to two or more crank engines, and in the case of the two crank engines it will be seen that one double acting pump piston would suffice, although I prefer to provide a separate pump for each pair of working cylinders.

Figures 4 and 5 illustrate an arrangement for a two crank engine wherein one pump is employed to supply all of the working cylinders. There are two pairs of working cylinders 1, 2 and 1^a, 2^a the cylinders of each pair having common combustion chambers 3 and 3^a respectively, and the cylinders 1 and 1^a being each provided with an exhaust port 10 and 10^a respectively while the cylinders 2 and 2^a are each provided with an inlet port 9 and 9^a respectively. The pump cylinder 11 is arranged between the pairs of working cylinders and is provided with fuel entrance port 15 controlled by the pump piston 12, and with fuel outlet ports 16 connected by passages 17 and 17^a respectively to the inlet ports 9 and 9^a. The crank pin to which the working pistons 4 and 5 are connected is displaced angularly relative to working pistons 4^a and 5^a contained in the working cylinders 1^a and 2^a, while the crank pin to which the pump piston 12 is connected is angularly displaced relative to both of the said crank pins, the arrangement being so chosen that the pump piston 12 and working pistons 4, 5, 4^a, 5^a tend to balance one another. It will be observed from the relative positions of the working pistons that in this engine the crank pin to which the pair of piston 4, 5 operate is angularly displaced relative to the crank pin to which the pair of working pistons 4^a and 5^a operate.

It is preferable to use valveless pumps for engines of very small powers only, and I may, with a view to increasing the efficiency of small powered engines, and I prefer in all cases of larger powered engines to, use a piston type of valve driven by an eccentric formed with a fixed to the crank shaft of

the engine or by any other suitable means to control the inlet and outlet of the fuel to and from the pump cylinder.

Figures 6 and 7 illustrate one example of an engine provided with a piston type valve to control the fuel. In these figures 1 and 2 indicate working cylinders provided with working pistons 4 and 5. The working cylinder 2 has an inlet port 9 connected by a passage 18 to a piston valve casing 19. A pump cylinder 11 is provided between the casing and the working cylinders and has a pump piston 12. The pistons 4, 5 and 12 are connected by connecting rods 6, 7 and 13 respectively to a crank shaft so as to balance one another and a valve rod 20 is also connected to the crank shaft by means of an eccentric formed with or fixed on the crank shaft. The valve rod 20 is connected to a valve 21, 22, 23 which controls a port 24 provided in the barrel of the pump cylinder 11. The piston valve consists of two end portions 21 and 23 fitting the bore of the valve casing 19 and of a middle portion 22 of reduced diameter. The outer end of the valve casing is connected by a pipe 25 to the fuel supply or carburetter.

In operation, the end 21 of the piston valve moves towards the crank shaft and uncovers the port 24 and the pump piston 12 draws the fuel into the cylinder 11. The end 21 of the valve prevents any possibility of the passage 18 communicating with the pipe 25. Movement of the piston valve away from the crank shaft causes the end 21 to arrive between the port 24 and the pipe 25 and uncover the port 24 to the passage 18, the end 23 preventing any escape from the passage from the inner end of the valve casing 19. The piston 12 is then able to force the fuel through the port 24 into the passage 18 from whence it passes through the inlet port 9 to the working cylinders. The arrows shown in Figure 11 indicate the path of the gases or vapour before and after combustion.

Figures 8 and 9 illustrate an example of a two crank engine wherein a pump is provided for each pair of working cylinders. A pump cylinder 11 is arranged alongside the working cylinders 1 and 2, and a pump cylinder 11^a is arranged alongside the working cylinders 1^a and 2^a. The pump piston 12 and the working pistons 4^a and 5^a are connected to crank pins 14 and 14^a the angular positions of which coincide with each other, while the pair of working pistons 4 and 5 and the pump piston 12^a are connected to crank pins 8 and 8^a respectively the angular positions of which coincide with each other but are angularly displaced 180 degrees relative to the crank pins 14 and 14^a. The arrangement of the pump ports, inlet ports and exhaust ports is a duplication of the similar ports described with reference

to Figures 3 and 4. The balance of this two crank engine is equally as perfect as that of a four cylinder engine working on the four cycle principle, while the turning moment is also similar owing to engine 70 working on the two cycle principle. The economy and balance of this engine is therefore equal to that of a four cylinder, four stroke engine and it furthermore runs absolutely silently. 75

Figures 10 and 11 illustrate another example of an engine provided with a piston type valve. The engine has a pair of staggered working cylinders 1 and 2, and a pair of staggered working cylinders 1^a and 2^a. A pump cylinder 11 is provided for the cylinders 1 and 2, while a pump cylinder 11^a is provided for the cylinders 1^a and 2^a. The crank pin 8 to which the pistons 4 and 5 belonging to the working cylinders 1 and 2 are connected is displaced 180 degrees relative to the crank pin 8^a to which the pistons 4^a and 5^a belonging to the working cylinders 1^a and 2^a are connected. The piston 12 belonging to the pump cylinder 11 is connected to a crank pin 14 which is angularly displaced 180 degrees relative to the crank pin 8, while the piston 12^a belonging to the pump cylinder 11^a is connected to the crank pin 8. 90

A piston valve 26—27—28 comprising two parts 26 and 28 jointed together by a reduced part 27 and having a closed lower end is provided with a port 29 in the part 28. The valve 26—27—28 is operated by an eccentric 29 provided on a lay shaft 30 which is driven from the crank shaft 18 by sprocket wheel and chain gearing, and controls three ports, 31, 32 and 33. The intake of the valve is situated at the top of the valve casing 34. The port 32 is connected by a common passage or chamber 35 to both the inlet ports 9 of both pairs of working cylinders. The port 31 is connected by a passage 36 to a port 16^a in the pump cylinder 11^a, and the port 33 is connected by a passage 38 to a port 16 in the pump cylinder 11. 100

During each revolution of the crank shaft 18, the valve 26—27—28 brings each pump cylinder once in succession into communication with the valve intake and each pump cylinder once in succession into communication with the passage or chamber 35 which is opened and closed to the working cylinders by the working pistons 5 and 5^a at the proper time. This engine also possesses substantially all the advantages of a four cylinder, four stroke engine combined with those of a two-stroke engine. 105

Any other suitable form or type of valve may be employed on engine in accordance with my invention, for example a sleeve valve or sleeve valves around the pump piston or pistons, or an automatic valve or valves, and so forth. 125

In crude oil engines, for example Diesel engines and Semi-Diesel engines, the pump or pumps are employed for pumping the scavenging air only, and the fuel is introduced into the working cylinders by other means, such as those in general use.

It is therefore to be understood that where the word "fuel" is employed this is to be understood as covering the construction wherein air only is supplied to the working pistons by the working pump, oil or other fuel being injected into the working cylinders when the said charge of air has been compressed by said working pistons approaching the top of their compression strokes.

What I claim is:

1. In an internal combustion engine the combination of a plurality of pairs of working cylinders, each pair having a common combustion chamber, a working piston in each cylinder, a plurality of pumps each having a piston, means to reciprocate a pair of working pistons and a pump piston together in unison, and means to reciprocate another pair of working pistons and another pump piston together in unison, each pair of working pistons moving with a pump piston substantially to balance the dynamic forces of the said other pistons, a mechanically operated valve to time the supply of fuel from each pump to one cylinder of each pair, and an exhaust port in the other cylinder of each pair.

2. In an internal combustion engine the combination of a plurality of pairs of working cylinders, each pair having a common combustion chamber, a working piston in each cylinder, a plurality of pumps each having a piston, means to reciprocate a pair of working pistons and a pump piston together in unison, and means to reciprocate

another pair of working pistons and another pump piston together in unison, each pair of working pistons moving with a pump piston substantially to balance the dynamic forces of the said other pistons, a mechanically operated valve to time the supply of fuel from each pump to one cylinder of each pair, and an exhaust port in the other cylinder of each pair.

3. In an internal combustion engine, the combination of a crank shaft, a pair of working cylinders arranged on a center line which is inclined to the plane of the crank shaft, a combustion chamber common to said cylinders, a pair of working pistons, connections between said pistons and said crank shaft, whereby the pistons move up and down in unison, a pump having a piston, and means for operating the pump piston in a direction opposed to that of the working pistons.

4. In an internal combustion engine, the combination of a plurality of pairs of working cylinders, the center line of each pair of cylinders being arranged at an inclination to the plane of the crank shaft, a combustion chamber common to each pair of cylinders, pistons in the cylinders, means to reciprocate the pistons of each pair of cylinders simultaneously in the same direction, a plurality of pumps, pistons therein, mechanical connections to said pump pistons, whereby each pump piston is reciprocated in the direction opposite to the movement of one pair of working pistons, an inlet port in one cylinder of each pair and an exhaust port in the other cylinder of such pair.

In testimony whereof I affix my signature.

JOHN DAVIDSON.
